CLAIM

The ornamental design for a gem setting, as shown.

DESCRIPTION

FIG. 1 is a perspective view of a gem setting showing my new design;

FIG. 2 is a top plan view of the invention;

FIG. 3 is a side elevational view of the invention, such view being symmetrical about a pedestal of the setting; FIG. 4 is a second side elevational view of the invention, such view being symmetrical about a gap between the pedestals of the setting;

FIG. 5 is a bottom plan view of the invention; and

FIG. 6 is a cross-sectional view taken on line 6—6 of FIG. 2 with gemstone shown in phantom.
